CLAIM

The ornamental design for a display screen with transitional graphical user interface for input setup, as shown and described.

DESCRIPTION

FIG. 1 is a front view of a first image in a sequence for an display screen with transitional graphical user interface for input setup;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof; and,

FIG. 12 is a front view of a twelfth image thereof.

The outermost broken line rectangle showing a display screen, as well as the broken lines showing text and other features are environmental only and form no part of the claimed design.

1 Claim, 4 Drawing Sheets
